UNITED STATES PATENT OFFICE.

ADONIAS D. BOLDUC, OF NEW BEDFORD, MASSACHUSETTS.

STOPPING MECHANISM FOR ROVING AND THE LIKE MACHINES.

Application filed July 23, 1923. Serial No. 653,814.

To all whom it may concern:

Be it known that I, ADONIAS D. BOLDUC, a citizen of the United States, residing at New Bedford, in the county of Bristol and 5 State of Massachusetts, have invented certain new and useful Improvements in Stopping Mechanism for Roving and the like Machines; and I do declare the following to be a full, clear, and exact description of 10 the invention, such as will enable others skilled in the art to which it appertains to make and use the same.

My invention relates to automatic stopping mechanisms for numerous kinds of machines and the present disclosure is directed to mechanisms of this character for use upon an American roving machine, the object being to provide an extremely simple and inexpensive, yet an efficient and reliable arrangement of parts which may be easily installed upon machines now in use, the construction being such as to bring the usual control means of the machine into play for stopping the latter in case of unusual movement of a selected part of the machine, such as the lower cone around which the usual belt passes. The construction herein disclosed is designed primarily to be actuated by dropping of the lower cone, in case the 30 belt breaks.

With the foregoing in view, the invention resides in the novel subject matter herein-after described and claimed, the description being supplemented by the accompanying 35 drawings.

Figure 1 is a fragmentary elevation partly in section, showing the application of my invention to a roving machine.

Figure 2 is a substantial duplicate of Fig. 40 1 with the exception that it illustrates the automatic stopping means in operative position, whereas Fig. 1 discloses the relation of parts when the machine is running.

Figure 3 is a fragmentary horizontal sectional view.

Figure 4 is an upper edge view of the actuator for the usual knock-off lever of the roving machine.

Figure 5 is a side elevation of the actuator 50 shown in Fig. 4.

Figure 6 is an elevation of a portion of the releasing means for the normally idle actuator.

In the drawings above briefly described, 55 the numerals 1 and 2 designate the usual upper and lower cones of a roving machine,

around which the well known belt 3 passes. Belt shifting guides 4 are engaged with this belt and by means of a rod or the like 5 are connected with the common slideable rack 6 for moving the belt to any desired position. The usual knock-off lever or control is indicated by the numeral 7 and a horizontal latch 8 is pivoted at 9 to said lever, said latch having a shoulder 17 to engage one 60 of the frame member 10 or other suitable part, to normally hold the lever 7 in position for running the machine. The latch 8 however is provided with a downturned end 11 adapted to be struck by a cam 12 on the rack 6, when the latter is moved sufficiently in one direction, thus releasing the latch and permitting the control lever 7 to be moved in a manner to throw the machine 65 out of operation.

At 13, I have illustrated the usual supporting means for the lower roll 2 which includes the usual roll-lifting rod 14. Very often, the belt 3 breaks and permits the roll 2 to fall, producing serious results in the 80 machine, well known to the trade. It is the object of my invention however, to provide a novel association of parts whereby the latch 8 is automatically released and an actuator simultaneously brought into play, 85 to shift the control lever 7 to an inoperative position, thus throwing the machine out of operation, in case the belt breaks and the cone 2 drops.

In the present disclosure, I provide a horizontally elongated actuator 15 in the form of a metal bar, said actuator being disposed by one side of the latch 8 and having a slot 16 in one end through which the pivot bolt or the like 9 passes for the purpose of connecting the actuator with the lever 7, yet permitting movement of said lever without moving the actuator. Near one end, the actuator 15 is provided with a latch portion 17 to engage the frame member or the like 100 10 as will be clear by reference to Figs. 1 and 5, thus holding said actuator against movement under the influence of the spring 18 which is connected at one end thereto. Means are provided however, whereby the 105 latch 8 and the actuator 15 are simultaneously released in case the cone 2 drops, thus permitting the spring 18 to come into play to shift the knock-off or control lever 7 to the position disclosed in Fig. 2 for the purpose of throwing the machine out of operation.

In the preferred form of construction, the actuator 15 is provided with a reduced downwardly extending end 19 whose lower extremity is bent to provide a horizontal yoke 20 which loosely surrounds the down turned end 11 of the latch 8, immediately under a pin 21 which extends laterally from said end 11. A horizontal releasing lever 22 is fulcrumed at 23 on a suitable part of the machine and one end underlies the yoke 20, while its other end is connected by a vertically adjustable rod 24 and a yoke 25, with the supporting means 13 for the lower cone 2.

15 By the construction and arrangement described or a substantial equivalent thereof, the controlling means of the machine, including the handle 7, is normally held in running position, by the latch 8, and the 20 latch portion 17° of the actuator 15 then holds the latter against movement under the action of the spring 18 but permits free movement of the lever 7 when latch 8 is released, during which movement the bolt or 25 the like 9 merely slides in the slot 16. In case the belt 3 should break however, the lower cone 2 drops, pulling downwardly upon the rod 24 and causing the lever 22 to force upwardly on the yoke 20 as disclosed 30 in Fig. 2. This yoke strikes the pin 21 as the actuator 15 is moved upwardly and hence said actuator and the latch 8 are simultaneously released from the part 10, permitting the spring 18 to come into play 35 and move the control means so as to stop the machine.

As excellent results may be obtained from the details disclosed, they may be followed 40 if desired, but within the scope of the invention as claimed, numerous minor changes may be made for adapting the invention to different types of machine.

I claim:

1. In combination, a machine having a 45 knock-off lever, a pivoted latch for normally holding said lever against movement, and manually controlled means for releasing said latch from a remote point; a normally held emergency actuator for said knock-off lever movably connected with the latter to permit operation thereof independently of said actuator when said latch is released, means for automatically releasing said actuator upon unusual operation of the machine, means operated by said actuator for automatically releasing said latch when said actuator is released, and means for automatically operating said lever when said latch is released.

60 2. The combination with a machine having means for controlling its operation, and means for holding said control means normally against operation; of an emergency actuator for said control means normally held against movement and having a connec-

tion with said control means permitting movement of the latter independently of the actuator, automatic releasing means for said holding means and said actuator adapted for actuation by unusual movement of a part 70 of the machine, and means for moving said actuator when released to operate said controlling means.

3. The combination with a machine having means for controlling its operation, and 75 a latch for holding said control means normally against operation; of an emergency actuator for said control means normally held against movement and connected with said means in a manner to permit movement of the latter without moving the actuator, and releasing means for said actuator adapted for actuation by unusual movement of a part of the machine, said actuator having a portion for releasing said 80 latch.

4. The combination with a machine having means for controlling its operation, and a latch for holding said control means normally against operation; of an emergency 90 actuator for said control means having a latch portion whereby it is normally held against movement, said actuator having a connection with said control means permitting movement of the latter independently 95 of the actuator, and releasing means for said actuator adapted for actuation by unusual movement of a part of the machine, said actuator having a portion for releasing said latch.

100 5. The combination with a machine having a lever for controlling its operation, and a latch pivoted to said lever for normally holding it against operation, said latch having a downturned free end co-operable with a latch releasing part of the machine; of an emergency actuator for said lever having a sliding connection with said lever to permit the latter to be moved independently of the actuator, said actuator having a latch portion by means of which it is normally held against operation, and having a releasing portion adjacent said downturned end of the aforesaid latch adapted to strike and release the latter upon release of said actuator, and releasing means for said actuator adapted for actuation by unusual movement of a part of the machine.

110 6. The combination with a machine having a lever for controlling its operation, and a latch pivoted to said lever for normally holding it against operation, said latch having a downturned free end cooperable with a latch releasing part of the machine; of an emergency actuator for said lever having a sliding connection with said lever to permit the latter to be moved independently of the actuator, said actuator having a latch portion by means of which it is normally held against operation and having a yoke 115 120 125 130

around said downturned end of the afore-
said latch adapted to strike and release the
latter upon release of said actuator, and re-
leasing means for said actuator adapted for
actuation by unusual movement of a part
of the machine.

7. A stopping attachment for a machine
having control means and a latch for such
means, said attachment comprising an ac-
tuator and means for slidably connecting it
to the machine control means in a manner
to permit operation of the latter independ-
ently of the actuator, said actuator having a
portion for engagement with a fixed part
15 of the machine to normally hold it against
operation and being provided with a por-
tion adapted to strike and release the above
named holding latch for the machine con-
trol means when the actuator is released, and
20 releasing means for said actuator adapted
to be operated by unusual movement of a
part of the machine.

8. A stopping attachment for a machine
having control means and a latch for such
means, said attachment comprising an ac-
tuator and means for connecting it with the

machine control means in a manner to per-
mit operation of the latter without moving
the actuator, said actuator having a portion
30 for engagement with a fixed part of the ma-
chine to normally hold it against operation
and being provided with a yoke on one end
to engage and release the above mentioned
holding latch for the machine control means
35 when the actuator is released, and releas-
ing means for said actuator adapted for
operation by unusual movement of a part of
the machine.

9. An actuator for a machine having con-
trol means and a latch for such means, said
actuator comprising a bar having a bolt-
receiving slot in one end permitting it to
40 be slidably connected to the machine con-
trol means, the other end of said bar having
a yoke to engage and release the above men-
tioned latch for the machine control means,
45 said bar having a latch portion adapted for
engagement with a fixed part of the ma-
chine to normally hold it against movement.

In testimony whereof I have hereunto af-
fixed my signature.

ADONIAS D. BOLDUC.
